REMOTELY CONTROLLED GUN MOUNT

George E. Barnhart, Pasadena, Calif.

Application November 14, 1939, Serial No. 304,335

12 Claims. (Cl. 89—41)

This invention relates to improvements in gun mounts.

The general object of this invention is to provide an improved device for mounting guns such as machine guns.

Another object of the invention is to provide a hydraulically operated machine gun mount which is adapted to move the gun to various positions and retain the gun in the adjusted position.

A further object of the invention is to provide a hydraulically operated machine gun mount wherein a plurality of the gun mounts may be interconnected for coordinated action.

A still further object of the invention is to provide in combination with the gun mount a hydraulically operated telescopic sight mount which is connected to the gun mount for coordinated action.

A still further object of the invention is a remotely controlled gun mount and a telescopic sight mount including means wherein actuation of the gun mount causes coordinated movement of the sight mount.

An additional object of my invention is to provide an improved gun control whereby the gun may be operated and/or sighted from a point remote from the gun.

A further object of the invention is to provide a novel gun control including a sighting means remote from the gun and wherein means is provided for correcting the sighting means to correct for the remote location of the sight.

An additional object of my invention is to provide a novel means for correcting the sight of a gun.

Another object is to provide a sight including novel means for advancing or retarding the sight, so that a speeding target may be properly led.

Other objects and the advantages of this invention will be apparent from the following description taken in connection with the accompanying drawings, wherein:

Fig. 1 is a fragmentary side view and section of an airplane showing a side view of my improved gun mount and telescopic sight mount;

Fig. 2 is a top plan view of a plurality of my improved gun mounts, telescopic sight mount and control valve and shows the connecting fluid conduits in broken lines;

Fig. 3 is an enlarged central vertical section through my improved gun mount;

Fig. 3A is a reduced fragmentary end view of the gun mount shown in Fig. 3;

Fig. 4 is a section taken on line 4—4, Fig. 3; 55

- Fig. 5 is a section taken on line 5—5, Fig. 3; Fig. 6 is a section taken on line 6—6, Fig. 3; Fig. 7 is a front view of the gun mount shown in Fig. 3 on a reduced scale showing the sight mount operating cylinders in section; 5 Fig. 7A is a section taken on line 7a—7a, Fig. 7; Fig. 8 is a reduced development of the sleeve member; 10 Fig. 9 is a reduced development of the interior of the housing member; Fig. 10 is a reduced development showing the outside of the master cylinder; Fig. 11 is a central vertical section through my improved telescopic sight mount; Fig. 12 is a section taken on line 12—12, Fig. 11; Fig. 13 is an enlarged section taken on line 13—13, Fig. 11; 20 Fig. 14 is a section taken on line 14—14, Fig. 11; Fig. 15 is an enlarged central vertical section through the gun mount control valve; Fig. 16 is a fragmentary section taken on line 16—16, Fig. 15; Fig. 17 is a fragmentary section taken on line 17—17, Fig. 15; Fig. 18 is a fragmentary section similar to Fig. 16 showing the valve turned to direct fluid to cause the gun mount to tilt downwardly; and Fig. 19 is a view similar to Fig. 18 showing the valve turned to direct fluid to cause the gun mount to tilt upwardly. 30 Although in the accompanying drawings I show my improved gun mount and sight mount associated with an airplane it will be understood that their use is not restricted solely to use on airplanes, but can be used on sea craft or land. Referring to the drawings I have indicated 40 my improved machine gun mount generally at 10. My improved telescopic sight mount is indicated generally at 12, the master control valve generally at 13 and one of the auxiliary gun mounts generally at 14. As shown the machine gun mount 10 includes a support member 14, a vertical operating portion 16 for causing lateral movement of the gun and a horizontal operating portion 17 for causing vertical action of the gun. 45 As shown the portion 17 includes a base member 18 having spaced upwardly extending end flanges 19 and 20 thereon and a centrally disposed depending hollow boss 21. The flange 19 has a cylindrical aperture 22 therein of greater 50 diameter than that of the aperture 22.

Positioned in the aperture 22 I provide a cylinder member 24 which is secured to the flange 19 by a plurality of keys 25 (see Fig. 4). The cylinder 24 projects beyond the flange 19 where it is externally threaded as at 26 to receive a threaded cap member 27 which closes the end of the cylinder. The cap member 27 includes a conduit portion 28 which is externally threaded to receive a coupling member 29 to secure thereto one end of a flexible conduit member 30.

The end of the cylinder 24 opposite the cap 27 is internally threaded as at 31 to receive an externally threaded plug member 32 which has a central aperture 33 and an offset, reduced, threaded aperture 34 therein.

Positioned in the central aperture 33 I provide a piston rod 35 having a packed piston head 36 on one end and the opposite end includes a reduced threaded portion 37. The plug member 32 includes a suitable packing gland member 38 surrounding the piston rod 35.

Positioned in the threaded aperture 34 of the plug member 32 I provide a rigid metal conduit member 39 which extends a predetermined distance beyond the plug 38 and is connected by a suitable coupling member 40 to one end of a conduit 41.

Surrounding the cylinder 24 I provide a sleeve member 42 the end of which adjacent the flange 20 is internally threaded as at 43 to receive a 30 threaded cap member 44.

The cap member 44 has a central aperture 45 therein through which the reduced threaded portion 37 of the piston rod 35 extends. The cap member 44 further includes an offset reduced aperture 46 through which the conduit 39 extends.

Mounted on the sleeve member 42 I provide a housing member 48 which at one side includes a reduced cylinder portion 49 (see Fig. 7). Both 40 ends of the cylinder 49 are open and internally threaded as at 50 and 51. One end of the cylinder 49 is closed by a threaded plug 52 which includes a conduit portion 53 connected by a suitable coupling member 54 to one end of a flexible conduit 55. The opposite end of the cylinder 49 is closed by a threaded plug 56 having a central aperture 57 and a plurality of reduced vent apertures 58 therein.

Positioned in the aperture 57 of the plug member 56 I provide a piston rod 59 which within the cylinder has a packed piston head 60 thereon and at the opposite end includes a reduced threaded portion 61.

Mounted on the reduced portion 61 of the piston rod 59 I provide a cross head 62 which extends towards the piston rod 35 and has an aperture 63 therein in which the reduced portion 37 of the piston rod 35 is positioned. A nut 64 on the threaded portion 61 of the piston rod 59 secures the cross head 62 to the piston rod 59 and a nut 65 on the threaded portion 37 of the piston rod 35 securely clamps the piston rod 35 to the cap member 44 and the cross head 62 to the cap member.

The housing 48 has a plurality of longitudinally extending, spiral keyways 66 therein (see Fig. 9), while the sleeve 42 has a plurality of longitudinally extending spirally arranged sets of keys 67 therein which are positioned in the keyways 66 of the housing 48 (see Figs. 4 and 8).

To prevent the sleeve 42 from rotating I provide a plurality of longitudinally extending sets of keys 68 therein (see Fig. 8) which are positioned in longitudinally extending keyways 69 in 75

the outer face of the cylinder 24 (see Figs. 4 and 10).

From the foregoing it will be apparent that when the piston 36 moves towards the flange 20 5 it will move the sleeve 42 with it and the keys 68 will cause it to move in a straight line thereby through the medium of the keys 67 cause the housing 48 to rotate upwardly in a clockwise direction. When the piston 36 and the sleeve 42 move towards the flange 19 the keys 67 cause the housing to rotate downwardly in an anti-clockwise direction. Furthermore when the piston rod 35 moves, the piston rod 59 is similarly moved through the medium of the cross head 62.

10 Positioned at a right angle to the cylinder 49 the housing 48 includes an outwardly extending post 70 having a plate member 71 thereon on which a machine gun assembly 72 is adapted to be secured by bolts 73 as shown in Fig. 1.

15 Positioned at a right angle to the cylinder 49 the vertical operating portion 16 includes a cylinder 74 which is internally threaded at the upper end as at 75 and at the lower end as at 76. Adjacent the lower end the cylinder is positioned in a bearing portion 77 of the support 15 and is prevented from rotating by a key 78. The upper end of the cylinder 74 is closed by a threaded plug member 79 having a central aperture 80 therein and the lower end of the cylinder 74 is closed by a similar plug member 81 having a central aperture 82 therein.

20 Positioned in the apertures 80 and 82 I provide a piston rod 83 which at the upper end includes a reduced threaded portion 84.

The upper plug member 79 includes a suitable packing gland 85 surrounding the piston rod 83 and the lower plug member 81 includes a similar packing gland 86 surrounding the piston rod 83.

25 Within the cylinder 74 the piston rod 83 includes a packed piston head 87. The piston rod 83 has two longitudinally extending conduits 88 and 89 provided therein. The upper end of the conduit 88 opens through the side of the piston rod above the piston head 87 and the conduit 89 opens through the side of the piston rod below the piston head 87. Adjacent the lower end the piston rod 83 includes a conduit portion 100 with which the conduit 88 communicates and which is connected by a suitable coupling member 101 to one end of a flexible conduit 102. Opposite the conduit portion the piston rod includes a similar conduit portion 103 with which the conduit 89 communicates and which is connected by a suitable coupling member 104 to one end of a flexible conduit 105.

30 Surrounding the cylinder 74 I provide a sleeve member 106 the upper end of which is internally threaded as at 107 to receive a threaded cap member 108.

The cap member 108 has a central aperture 109 and a plurality of vent apertures 110 therein. The reduced portion 84 of the piston rod 83 is positioned in the central aperture of the cap member 108 and the two are firmly secured together by a nut 112. Thus when the piston rod 83 moves it, through the medium of the cap member 108, moves the sleeve 106.

35 Mounted on the sleeve 106 I provide a housing member 113 which at one side includes a reduced cylinder portion 114 (see Fig. 7). The housing 113 is rotatably mounted in spaced bearing portions 115 of the support 15 and includes enlarged flanges 116 which engage the adjacent faces of the bearing portions 115 to prevent vertical movement of the housing. The upper portion of the housing 113 above the upper bearing 116 is posi-

tioned in the hollow boss 21 of the base member 18 and is secured thereto by a key 117 and a set screw 118.

Both ends of the cylinder 114 are open and internally threaded as at 119 and 120. The upper end of the cylinder 114 is closed by a threaded plug 121 which includes a conduit portion 122 connected by a suitable coupling member 123 to one end of a flexible conduit 124. The lower end of the cylinder 114 is closed by a plug member 125 having a central aperture 126 and a plurality of reduced vent apertures 127 therein.

Positioned in the central aperture 126 of the plug 125 I provide a piston rod 128 which within the cylinder 114 has a packed piston head 129 thereon and at the opposite end includes a reduced threaded portion 130.

Mounted of the reduced portion 130 of the piston rod 128 I provide a cross head 131 which extends towards the sleeve 106 and has a portion 132 surrounding the sleeve which is secured thereto by a set screw 133. A nut 134 on the threaded portion 130 of the piston rod 128 secures the cross head to the piston rod 128.

The housing 113 has a plurality of longitudinally extending spiral keyways 135 therein similar to the keyways 66 of the housing 48.

The sleeve 106 has a plurality of longitudinally extending spirally arranged sets of keys 136 therein similar to the keys 67 of the sleeve 42. The keys 136 are positioned in the housing keyways 135.

To prevent the sleeve 106 from rotating I provide a plurality of longitudinally extending sets of keys 137 therein similar to the keys 68 of the sleeve 42 (see Fig. 6). The keys 137 are positioned in longitudinally extending keyways 138 in the outer face of the cylinder 74 similar to the keyways 69 in the cylinder 24.

From the foregoing it will be apparent that when the piston 87 moves downwardly it will move the sleeve 106 with it and the keys 137 will cause it to move in a straight line thereby through the medium of the keys 136 cause the housing 133 to rotate in a clockwise direction. When the piston 87 and the sleeve 106 move upwardly, the keys 136 cause the housing 113 to rotate in an anti-clockwise direction. Furthermore when the sleeve 106 moves, the piston 129 is similarly moved through the medium of the cross head 131.

When the device 10 is mounted for operation the support 15 is adapted to be clamped by any suitable means to a supporting structure provided for that purpose.

My improved sight mount 12 is shown in detail in Figs. 11 to 14, inclusive, and includes a vertical support member 140 having a telescope carrier 141 rotatably mounted thereon. As shown the telescope carrier 141 includes a central hollow housing 142 having an enlarged recess in the bottom hereof in which the upper end of a sleeve 144 which surrounds the support 140 is positioned. The upper end of the sleeve 144 is closed by a threaded cap 145 and the upper end of the support 140 is closed by a cap 146. The adjacent faces of the caps 145 and 146 include circular raceways in which balls 147 are positioned to form an anti-friction bearing. The housing 142 and the sleeve 144 are secured together by a set screw 148.

One side of the housing 142 includes a projecting horizontal cylinder portion 149 and the opposite side of the housing includes a horizontal projecting cylinder portion 150. At the inner end

of the cylinder 150 the housing includes a coaxial, enlarged, threaded recess 151. The outer end of the cylinder 149 is threaded as at 152 and is closed by a threaded plug member 153 and the outer end of the cylinder is similarly threaded as at 154 and closed by a threaded plug member 155 having a vent aperture 156 therein.

The cylinder 149 has a cylinder portion 157 depending therefrom, which is of the same internal diameter as the cylinder 149 but is of less length. A conduit 158 communicates with the interior of both cylinders adjacent the outer ends thereof.

The outer end of the cylinder 157 is threaded as at 159 and closed by a threaded plug member 160 which includes a conduit portion 161 connected by a suitable coupling member 162 to one end of a flexible conduit 163. The opposite end of the cylinder is threaded as at 164 and closed by a threaded plug 165 having a central aperture 166 and a plurality of vent apertures 167 therein.

Positioned in the central aperture 166 of the plug member 165 I provide a piston rod 168 a portion of which is threaded as at 169. Within the cylinder 157 the piston rod 168 has a packed piston head 170 thereon and the threaded portion 169 of the piston rod is engaged by a nut member 171 which is retained in engagement with the plug member 165 by a spun over portion 172 thereon engaging a flange on the nut.

Surrounding the piston rod 168 within the cylinder 157 between the piston head 170 and the inner face of the plug 165 I provide a coiled spring 174.

Positioned in the threaded recess 151 I provide an externally threaded plug 175 which has a bore 176 therein coaxial with the cylinders 149 and 150 and of the same size. Positioned in the cylinders 149 and 150 and the bore 176 I provide a rod member 177 having in the outer surface thereof a pair of opposed straight spline keyways 178.

The cylinder portion 150 has a pair of opposed slots 179 therein in each of which a spline member 180 is positioned which extends into its associated keyway 179 to prevent rotation of the rod 177. The spline members 180 are shown as retained in the cylinder 150 by a collar 181 surrounding the cylinder and secured thereto by a set screw 182.

The rod 177 further includes a pair of opposed longitudinally extending spiral keyways 183. Within the cylinder 149 the rod 177 includes a reduced portion 184 having a packed piston head 185 thereon.

Within the cylinder 150 between the end of the rod 177 and the inner face of the plug member 155 I provide a coiled expansion spring 186.

Surrounding the rod 177 between the inner end of the cylinder 149 and the plug member 175 I provide a sleeve member 187 which intermediate its length has a pair of opposed spline members 188 therein which are arranged at an angle to correspond to the pitch of the spline keyways 183 in the rod 177 in which they are positioned. Each face of the sleeve 187 has a circular ball race groove therein in which are positioned a plurality of anti-friction balls 189.

Surrounding the rod 177 between the inner end of the cylinder 149 and the adjacent face of the sleeve 187 I provide a plate 190 which the anti-friction balls 189 at that end of the sleeve engage. Surrounding the rod 177 between the inner face of the plug 175 and the adjacent face

of the sleeve 187 I provide a plate member 191 which the anti-friction balls at that end of the sleeve engage. The plug member 175 is adapted to be adjusted to maintain the correct pressure on the anti-friction balls 189 at all times.

Surrounding the sleeve 187 I provide a cylindrical housing member 192 having a gear toothed segment 193 extending therefrom.

Extending upwardly therefrom the housing 142 includes a pair of spaced legs 194 between which a telescope gimbal ring 195 is pivotally supported on trunnions 196.

The gimbal ring 195 includes a depending gear toothed segment 197 which meshes with the segment 193. The gimbal ring supports a sight member 198 which may be of any desired type.

When the rod 177 is axially moved as will hereinafter be described, the spiral keyways cause the splines 188 to rotate the sleeve 187 and housing 192 whereupon through the medium of the gear segments 193 and 197 the telescope 198 will be tilted in one direction or another depending on which direction the rod 177 is moved.

Below the housing 142 and at the side of the support 140 I provide a horizontal tube 199 which includes a cylindrical chamber 199' at one side of the support and a cylindrical chamber 199'' on the opposite side and has an aperture 199a through one side thereof intermediate the two cylinder portions.

The tube 199 is supported in bearing portions 199b and 199c of a bracket member 199d which includes a hollow boss portion 199e surrounding the support and secured thereto by a bolt 199f and nut 199g.

The outer end of the cylinder portion 199' is internally threaded as at 200 and is closed by a solid threaded plug member 201 and the outer end of the cylinder portion 199'' is internally threaded as at 202 and is closed by a threaded plug member 203 having a vent aperture 204 therein.

Depending therefrom the cylindrical portion 199' includes a cylindrical portion 205 which is of the same internal diameter as the portion 199' but is of less length.

A conduit 206 affords communication between the cylinders 199b and 205 adjacent the outer ends thereof.

The outer end of the cylinder 205 is internally threaded as at 207 and is closed by a threaded plug 208 which includes a conduit portion 209 connected by a suitable coupling member 210 to one end of a flexible conduit 212. The opposite end of the cylinder is threaded as at 213 and closed by a plug member 214 having a central aperture 215 and a plurality of reduced vent apertures 216 therein.

Positioned in the central aperture 215 of the plug member 214 I provide a piston rod 217 which includes a threaded portion 218. Within the cylinder 205 the piston rod 217 has a packed piston head 219 thereon and exterior thereof is engaged by a nut 220. The nut 220 is retained in engagement with the plug member 214 by a spun over portion 221 thereon engaging a flange on the nut.

Surrounding the piston rod 217 within the cylinder 205 between the piston head 219 and the inner end of the plug member 214 I provide a coiled expansion spring 222.

Positioned in the cylindrical portion 199' I provide a packed piston head 223 and positioned in the cylindrical portion 199'' I provide a slide head 224 which is prevented from rotating by a

spline member 225 (see Fig. 12) in the cylinder 192.

The piston head 223 and the slide head 224 are connected by a rigid piston rod 226 the side of which nearest to the support 15 is provided with a gear toothed rack portion 227.

Mounted on the vertical sleeve 144 I provide a collar 228 having a segment of gear teeth 229 thereon which extends through the aperture 193 in the tube 190 and meshes with the gear toothed rack portion 227 of the piston rod 226. The collar 228 is shown as secured to the sleeve 144 by a key 230 and by nuts 231 on a threaded portion 232 of the sleeve.

Positioned in the cylinder portion 199'' between the slide head 224 and the inner end of the plug member 203 I provide a coiled expansion spring 233.

When the piston rod 226 is reciprocated as will be described hereinafter the rack 227 rotates the collar 228 which in turn through the medium of the vertical sleeve 144 swings the telescope mount 141 about the axis of the support either to the right or the left depending upon which direction the piston rod 226 is moved.

The flexible conduit 163 of the telescope sight mount 12 is connected by a conduit indicated by the broken lines 235 in Fig. 2 to the flexible conduit 55 of the gun mount 10 and the flexible conduit 212 of the telescope sight mount 12 is connected by a conduit indicated by the broken lines 236 to the flexible conduit 124 of the gun mount 10.

Thus it will be seen that when the horizontal sleeve 42 of the gun mount is moved outwardly by the piston 36 and the housing 48 rotates in a clockwise direction to elevate the machine gun 72 thereon, the piston 60 draws fluid into the cylinder 49 from the telescope mount cylinders 149 and 157 whereupon the spring 186 forces the rod 177 towards the cylinder 149 thereby rotating the housing 192 and causing the telescope sight 198 to be swung upwardly.

When the direction of the gun mount piston 60 is reversed fluid is forced from the cylinder 49 into the cylinders 149 and 157 whereupon the piston 185 moves the rod 177 against the action of the spring 186 and the telescope sight 198 is swung downwardly.

By adjusting the piston 170 by means of the nut 171 the volume in the cylinders 149 and 157 may be varied to either cause the telescope to lead or trail the elevating action of the gun mount 10.

When the vertical sleeve 106 of the gun mount moves downwardly to rotate the gun mount in an anti-clockwise direction, the piston 129 draws fluid into the cylinder from the cylinder 114 from the telescope sight mount cylinders 199' and 205 whereupon the spring 223 forces the piston rod 226 towards the cylinder 199' thereby rotating the telescope mount 141 about its axis in an anti-clockwise direction or to the left.

When the direction of the gun mount piston 129 is reversed, fluid is forced from the cylinder 114 into the cylinders 199' and 205 and the piston rod 226 is moved against the action of the spring 223 whereupon the telescope mount 141 is swung about its axis in a clockwise direction or to the right.

The auxiliary gun mount 14 shown in Fig. 2 is constructed and operates similar to the gun mount 10 previously described except that the telescope mount operating cylinders 49 and 114 and their associated parts are omitted. I have

therefore indicated like portions of the auxiliary gun mount 14 by similarly primed reference numerals.

When the auxiliary gun mount 14 is used the flexible conduit 30 of the gun mount 10 is connected to the flexible conduit 30' of the gun mount 14 by a conduit indicated by the broken lines 237 and the flexible conduit 41 of the gun mount 10 is connected to the flexible conduit 41' of the gun mount 14 by a conduit indicated by the broken lines 238.

Similarly the flexible conduit 102 of the gun mount 10 is connected to the flexible conduit 102' of the gun mount 14 by a conduit indicated by the broken lines 239 and the flexible conduit 105 of the gun mount 10 is connected to the flexible conduit 105' of the gun mount 14 by a conduit indicated by the broken lines 240.

The master control valve 13 is shown in detail in Figs. 14 to 19, inclusive, and comprises two separate valve mechanisms, a vertical control valve 245, and a horizontal movement control valve 246.

The vertical movement control valve 245 includes a body portion 247 having a hollow base 248 which is adapted to be secured to a supporting structure by bolts 249. The body 247 has a tapered recess 250 therein in which a tapered valve plug 251 is positioned and which includes a valve stem 252 projecting out of the body through an aperture 253. The outer portion of the valve stem 252 includes a reduced polygonal portion 254 and a further reduced threaded portion 255.

The body 247 includes an elongated, depending, externally threaded inlet conduit 256 having an externally threaded lateral conduit portion 257 intermediate the end thereof and the body 247. Opposite the inlet conduit portion 257 the body 247 includes an elongated angularly extending externally threaded outlet conduit portion 258 having a lateral externally threaded conduit portion 259 intermediate the end thereof and the body 247.

Between the conduits 256 and 258 the body at one side includes an externally threaded conduit 260 and opposite the conduit 260 an externally threaded conduit 261.

The valve plug 251 has a conduit 262 and a conduit 263 therein. The ends of the conduits 262 and 263 are arranged at 90° to each other so that in one position of the valve plug 251 the conduit 263 communicates with the outlet conduit 258 and with the conduit 260 and the conduit 263 communicates with the conduit 261 and the inlet conduit 256 as shown in Fig. 18. In another position of the valve plug 251 the conduit 262 communicates with the inlet conduit 256 and the conduit 260 and the conduit 263 communicates with the outlet conduit 258 and the conduit 261 as shown in Fig. 19. When the valve plug 251 is in a closed position as shown in Fig. 16, the valve plug conduits 262 and 263 do not communicate with any of the housing conduits 256, 258, 260 or 261.

The horizontal movement control valve 246 includes a body portion 264 having a tapered recess 265 therein in which a tapered valve plug 266 is positioned which includes a valve stem 267 which projects through an aperture 268 and has an operating handle 269 thereon. The housing 264 includes an externally threaded inlet conduit 270 and opposite an externally threaded outlet conduit 271. Arranged at 90° to the conduits 270 and 271 the body 264 includes at one side an externally threaded conduit 272 and opposite an

externally threaded conduit 273. The body 264 further includes a depending arm portion 264a having a polygonal aperture 264b therein in which the polygonal portion 254 of the valve 245 is positioned. A nut 264c firmly clamps the arm 264a to the valve stem 252 of the valve 245.

The valve plug 266 has a conduit 274 and a conduit 275 therein the opposite ends of each of which are arranged at 90° to each other similar to the conduits 262 and 263 of the valve plug 251. Similar to the conduits of the valve plug 251 the conduits 274 and 275 of the valve plug 266 are adapted to direct fluid from the inlet conduit 270 to one of the conduits 272 or 273 or direct fluid from the conduits 272 or 273 to the outlet conduit 271.

The inlet conduit 270 has one end of a flexible conduit 276 secured thereto by a suitable coupling member 277. The opposite end of the flexible conduit 276 is connected to the conduit 257 by a suitable coupling member 278 (see Fig. 16).

The outlet conduit 271 has one end of a flexible conduit 279 connected thereto by a suitable coupling member 280. The other end of the flexible conduit 279 is connected by a suitable coupling member 281 to the outlet 258 (see Fig. 16).

The conduit 272 has one end of a flexible conduit 282 connected thereto by a suitable coupling member 283 and the conduit 273 has one end of a flexible conduit 284 connected thereto by a suitable coupling member 285 (see Fig. 17).

The inlet conduit 256 has a supply conduit 286 connected thereto by a suitable coupling member 287 and the conduit 259 on the outlet conduit 258 has a return conduit 288 connected thereto by a suitable coupling member 289.

The conduit 286 is adapted to be connected to the main fluid pressure line of the airplane (not shown) and the conduit 289 is adapted to be connected to the main fluid return line of the airplane.

The conduit 260 has one end of a conduit 290 connected thereto by a suitable coupling member 291 and the conduit 261 has one end of a conduit 292 connected thereto by a suitable coupling member 293 (see Fig. 16).

As shown in Fig. 1 the conduit 292 is connected to the conduit 238 by a conduit indicated by the broken lines 295 and the conduit 290 is connected to the conduit 237 by a conduit indicated by the broken lines 296.

The conduit 284 is connected to the conduit 240 by a conduit indicated by the broken lines 297 and the conduit 282 is connected to the conduit 239 by a conduit indicated by the broken lines 298.

In operation when the operator desires to elevate the machine guns 72 and 72' he grasps the operating handle 269 of the master control valve 13 and without turning it swings the unit 246 towards himself thereby rotating the valve plug 251 of the unit 245 to the position shown in Fig. 19 wherein the valve plug conduit 262 communicates with the inlet conduit 256 and the conduit 260 and the valve plug conduit 263 communicates with the conduit 258 and the outlet conduit 261. Whereupon fluid under pressure is directed from the source through the conduits 290 and 296 into the conduit 237 and thence through the conduits 30 and 30' into the horizontal cylinder of each gun mount causing actuation thereof to tilt the guns upwardly as previously described. The fluid exhausted from the gun mount cylinders on this operation flows through the conduits 41 and 41' into and through

the conduit 238 and thence through the conduits 295 and 292 to the valve conduit 258 and through the plug valve conduit 263 and the outlet conduit 258 into the return conduit 288.

When the operator desires to tilt the guns 72 and 72' downwardly he swings the valve unit 246 away from himself thereby rotating the valve plug 251 to the position shown in Fig. 18 wherein the valve plug conduit 263 communicates with the inlet conduit 256 and the conduit 261 and the valve plug conduit 262 communicates with the outlet conduit 258 and the conduit 260. Whereupon fluid under pressure is directed from the source through the conduits 292 and 295 into and through the conduit 238 and thence through the conduits 41 and 41' into the horizontal cylinders of the gun mounts causing actuation thereof to tilt the guns downwardly as previously described. The fluid exhausted from the gun mount cylinders on this operation flows through the conduits 30 and 30' into and through the conduit 237 and thence through the conduits 296 and 290 and through the valve conduits 260, 262 and 258 into the return conduit 288.

As the machine guns swing up or down as described the telescopic sight mount 12 is actuated for similar movement as previously described.

When the operator wishes to swing the machine guns 72 and 72' to the right he rotates the operating handle 269 of the master control valve 13 towards the right whereupon the valve plug conduit 274 of the unit 246 communicates with the inlet conduit 270 and the conduit 272 and the valve plug conduit 275 communicates with the conduit 273 and the outlet conduit 271. Whereupon fluid under pressure is directed from the source through the conduits 283 and 298 into and through the conduit 239 and through the conduits 102 and 102' into the vertical cylinders of the gun mounts thereby causing actuation of the gun mount as previously described to swing the guns towards the right.

The exhaust fluid from the gun mount cylinders on this operation flows through the conduits 105 and 105' into and through the conduit 240 and through the conduits 297 and 284 and thence through the valve conduit 273 and through the valve plug conduit 275 into the valve outlet conduit 271.

When the operator wishes to swing the machine guns 72 and 72' to the left, he rotates the control handle 269 of the master valve to the left thereby rotating the valve plug to a position wherein the valve plug aperture 274 communicates with the inlet aperture 270 and the conduit 273. Whereupon fluid under pressure flows from the source through the conduits 284 and 297 into and through the conduits 105 and 105' into the vertical cylinders of the gun mounts thereby causing actuation of the gun mounts as previously described to swing the guns toward the left. The exhaust fluid from the gun mount cylinders on this operation flows through the conduits 102 and 102' into and through the conduit 239 into the conduits 298 and 282 and through the valve conduit 272. Thence through the valve plug conduit 275 into the outlet conduit 271.

As the machine guns swing to the right or left as just described, the telescopic sight mount 12 is actuated for similar movement.

In using my improved device, the sight may be remote from the gun. The gun is trained on the target and the target is watched through the sight. When the sight is on the target the 75

gun is fired. The location of the "strike" of the missile is noted. The members 171 and 220 are then adjusted to bring the position of the strike into line with the sight. The sight and gun are then both pointed to the position of the strike. The gun is then shifted to point towards the target and its movement noted through the sight. When the sight and target are in line the guns are fired and the missile strikes the target. Successive corrections may be applied as desirable.

From the foregoing description it will be apparent that I have provided novel remotely controlled gun mount and a sight mount and have provided novel means for coordinating the actuation of the gun mount and the sight mount and for correcting due to the fact that the gun sight is remote from the gun.

Having thus described my invention I claim:

1. In a gun mount, a support, a cylindrical housing swivelled on said support, hydraulic piston operated means in said housing, means operated by said piston means for rotating said housing, a base surmounting said housing, a cylinder on said base, a tilting housing member having a gun base rotatably mounted on said housing, other hydraulic operated piston means on said cylinder, means operated by said other piston means for rotating said housing member, a sight member and hydraulic means operated by said piston means for shifting the sight member.

2. In a gun mount, a support, a cylindrical housing swivelled on said support, hydraulic piston operated means in said housing, means operated by said piston means for rotating said housing, a base surmounting said housing, a cylinder on said base, a tilting housing member having a gun base and mounted on said housing, other hydraulic operated piston means on said cylinder and means operated by said other piston means for rotating said housing member, a sight member remote from the gun base and means for shifting said sight member as gun base is shifted.

3. In a gun mount, a support, a cylindrical housing swivelled on said support, hydraulic piston operated means in said housing, means operated by said piston operated means for rotating said housing, a base surmounting said housing, cylinder on said base, a tilting housing member having a gun base and rotatably mounted on said housing, other hydraulic operated piston means on said cylinder, means operated by said other piston means for rotating said housing member, a sight member, hydraulic means operated by said piston means for shifting the sight member and means to adjust the degree of shift of the sight member relation to the piston member.

4. In a gun mount, a support, a cylindrical housing swivelled on said support, hydraulic means for swivelling said housing including a cylinder having a piston and a piston rod thereon, means operated by said hydraulic means for shifting said piston, a base surmounting said housing, a housing member tiltably mounted on said base, other hydraulic means for tilting said housing, said tilting housing including a gun base and including a second cylinder having a second piston, a second piston rod on the second piston, means operated by said other hydraulic means for shifting said second piston rod, a telescopic sight mount, means to swivelly and tiltably support said sight mount and means operated by said piston rods for swivelling and tilting said sight mount.

5. In a gun mount, a support, a cylindrical

housing swivelled on said support, means for swivelling said housing including a cylinder having a piston and a piston rod thereon, a base surmounting said housing, a gun base housing member tiltably mounted on said base, means for tilting said housing, said housing tilting means including a second cylinder including a second piston, sight mount, means to swivelly and tiltably support said sight mount, means operated by said pistons for swivelling and tilting said mount and means to change the position of the sight mount relative to the position of the gun mount.

6. In a gun mount, a support, a cylindrical housing swivelled on said support, means for swivelling said housing including a cylinder having a piston and a piston rod thereon, hydraulic means for shifting said piston, a base surmounting said housing, a housing member tiltably mounted on said base, means for tilting said housing, said tilting housing including a gun base, and including a second cylinder including a second piston, a second piston rod on the last mentioned piston, hydraulic means for shifting said second piston, a sight mount, means to swivelly and tiltably support said sight mount and means operated by said pistons for swivelling and tilting said mount and means to change the position of the sight mount relative to the position of the gun mount.

7. In a gun mount, a support, a cylindrical housing swivelled on said support, a cylinder within said housing, a piston in said cylinder, means to direct fluid into said cylinder to axially shift said piston, means whereby axial movement of said piston rotates said housing, a base surmounting said housing, a horizontal cylinder on said base, a sleeve surrounding said horizontal cylinder, a tilting housing member having a gun base and surrounding said sleeve, a piston in said horizontal cylinder and including a piston rod connected to said last mentioned sleeve, means to direct fluid into said horizontal cylinder, means whereby when said last mentioned sleeve is moved axially said housing is tilted, a sight member remote from the gun base and means to shift the sight member as the gun base is shifted.

8. In a gun mount, a support, a cylindrical housing swivelled on said support, a cylinder within said housing, a piston in said cylinder, means to direct fluid into said cylinder to axially shift said piston, means whereby axial movement of said piston rotates said housing, a base surmounting said housing, a horizontal cylinder on said base, a sleeve surrounding said horizontal cylinder, a tilting housing member having a gun base and surrounding said sleeve, a piston in said horizontal cylinder and including a piston rod connected to said last mentioned sleeve, means to direct fluid into said horizontal cylinder, means whereby when said last mentioned sleeve is moved axially said housing is tilted, a sight member, hydraulic means operated by said piston means for shifting the sight member and means to adjust the degree of shift of the sight member relative to the piston member.

9. In a gun mount, a support, a cylindrical housing swivelled on said support, a cylinder within said housing, a piston in said cylinder, means to direct fluid into said cylinder to axially shift said piston, means whereby axial movement of said piston rotates said housing, a horizontal cylinder on said base, a sleeve surrounding said horizontal cylinder, a tilting housing member having a gun base and surrounding said sleeve, a

75 piston in said horizontal cylinder and including a piston rod connected to said last mentioned sleeve, means to direct fluid into said horizontal cylinder, and means whereby when said last mentioned sleeve is moved axially said housing is tilted, a sight member and hydraulic means operated by said piston means for shifting the sight member.

10. In a gun mount, a support, a cylindrical housing swivelled on said support, a sleeve in said housing, a cylinder in said sleeve and anchored to said support, a piston in said cylinder and having a piston rod connected to the sleeve and projecting from both ends of said cylinder, means 10 to direct fluid into either end of said cylinder to axially shift said piston sleeve, means whereby axial movement of said sleeve rotates said housing, a base surmounting said housing, a horizontal cylinder on said base, a sleeve surrounding 15 said horizontal cylinder, a tilting housing member having a gun base and surrounding said sleeve, a piston in said horizontal cylinder and including a piston rod connected to said last mentioned sleeve and extending through one end of said horizontal cylinder, means to direct fluid into either end of said horizontal cylinder, and means whereby when said last mentioned sleeve is moved axially said housing is tilted.

11. In a gun mount, a support, a cylindrical housing swivelled on said support, a cylinder within said housing, a piston in said cylinder, means to direct fluid into said cylinder to axially shift said sleeve, means whereby axial movement of said piston rotates said housing, said housing 30 including a lateral reduced cylinder having a piston and a piston rod thereon connected to said sleeve, and extending from one end and having an inlet conduit at the other end, a base surmounting said housing, a horizontal cylinder on said base, a sleeve surrounding said horizontal cylinder, a tilting housing member surrounding said sleeve, a piston in said horizontal cylinder and including a piston rod connected to said last 35 mentioned sleeve, means to direct fluid into said horizontal cylinder, means whereby when said last mentioned sleeve is moved axially said housing is tilted, said tilting housing including a gun base and including a reduced cylinder having a piston therein connected to said horizontal sleeve and having a piston rod extending from one end thereof and having an inlet at the other end, a telescopic sight mount including a support member having a body rotatably mounted thereon and including opposed cylinder portions, a rod member 40 having a piston head positioned in one cylinder portion and engaged by a spring in the other cylinder portion, a housing member surrounding said rod intermediate said portions, a telescopic sight member mounted on said sight 45 mount and means operated by fluid pressure in said reduced cylinders for operating said sight member.

12. In a gun mount, a support, a cylindrical housing swivelled on said support, a means for 45 swivelling said housing, said housing including a cylinder having a piston and a piston rod thereon, hydraulic means for shifting said piston, a base surmounting said housing, a housing member tiltably mounted on said base, other means 50 for tilting said housing, said tilting housing including a gun base and including a second cylinder including a second piston, a second piston rod on the last mentioned piston means, hydraulic means for shifting said second piston, a telescopic sight mount including a support member having 55

a body rotatably mounted thereon and including a cylinder portion, a rod member having a piston head positioned in the cylinder portion, a spring engaging the rod, a housing member surrounding said rod, a telescopic sight member mounted on said body and meshing gear toothed segments on said housing member and said sight member, means whereby when said rod is axially moved said member will be rotated, an auxiliary cylinder adjacent said first sight mount cylinder and communicating with the interior of the first reduced cylinder portion adjacent the outer end thereof, said auxiliary cylinder including an inlet conduit, means to vary the fluid contained volume of said auxiliary cylinder, means whereby movement of said gun mount reduced piston will cause move- 15

ment of said sight mount piston, said sight mount including a frame member, an elongated cylinder on said frame member, a piston rod in said last mentioned cylinder and having a piston thereon, meshing gear toothed members on said body and frame member piston rod, a second auxiliary cylinder adjacent said piston end of said elongated cylinder and communicating therewith, said second auxiliary cylinder including an inlet conduit, means to vary the fluid volume of said second auxiliary cylinder, and means whereby when said vertical reduced cylinder piston is moved it causes actuation of said piston in said elongated cylinder of said sight mount.

GEORGE E. BARNHART.
